UNITED STATES PATENT OFFICE

2,614,855

ANIMAL SIMULATING VELOCIPED

Francis B. Lolmaugh, Plymouth, Ind.

Application July 28, 1950, Serial No. 176,470

1. Claim. (Cl. 280—1.203)

1

This invention relates to new and useful improvements and structural refinements in velocipedes, and the principal object of the invention is to provide a velocipede in the form of a toy horse which may be conveniently and effectively propelled along the ground or floor and which may be easily steered by the rider.

Some of the advantages of the invention reside in its simplicity of construction, in its pleasing appearance, in its efficient maneuverability, and in its adaptability to economical manufacture.

With the above more important objects and features in view, and such other objects and features as may become apparent as this specification proceeds, the invention consists essentially of the arrangement and construction of parts as illustrated in the accompanying drawings, in which:

Figure 1 is a side elevational view of the invention, this being partially broken away so as to reveal its construction;

Figure 2 is a top plan view thereof, also partially broken away;

Figure 3 is a sectional view, taken substantially in the plane of the line 3—3 of Figure 1;

Figure 4 is a fragmentary sectional detail, taken substantially in the plane of the line 4—4 in Figure 2;

Figure 5 is a fragmentary rear elevational view of one of the leg members;

Figure 6 is a transverse sectional detail, taken substantially in the plane of the line 6—6 in Figure 1; and

Figure 7 is a perspective view of the reins or steering bar used in the invention.

Like characters of reference are employed to designate like parts in the specification and throughout the several views.

Referring now to the accompanying drawings in detail, the invention consists of a velocipede which is designated generally by the reference character 10 and assumes the form of a toy horse having an elongated body consisting of a front section 12 and a rear section 14.

The body sections 12, 14 are hollow and are preferably formed from sheet material having suitable covering thereon, and are pivotally connected together by a hinge assembly 16 having a vertical hinge pin 18 provided with suitable anti-friction bearings 19, whereby the front section 12 may be swung laterally to one side or the other with respect to the rear section 14.

A sleeve 20 of flexible tubing, or a coil spring, interwoven with cloth encloses the hinge as-

2

sembly 16 so as to hide the same from view, the opposite end portions of this sleeve being stretched over the adjacent end portions of the respective body sections 12, 14 so as to retain the sleeve in position but permit relative pivotal movement of the two sections to facilitate steering. The end portions of the sleeve 20 are provided with eyelets to receive suitable screws 21, whereby the sleeve is secured to the body sections 12, 14.

10 As is best shown in Figure 2, the front end wall 22 of the rear section 14 may be substantially flat while the rear end wall of the front section 12 may be beveled as at 23 so as to afford sufficient clearance while steering.

15 A blanket 24 covers the sleeve 20 and extends on the rear section 14 substantially beyond the rear edge of the sleeve, suitable straps and buckles 25 being used to secure the blanket in place.

20 A convenient seat or saddle 26 is mounted on the rear body section 14 and covers an upper portion of the blanket 24, while a bridle strap iron 28 is provided at the free ends thereof with a pair of eyes 30 which are secured to opposite sides of the "head" 32 of the front portion 12 by the screws 31, the yoke 28 extending rearwardly from the "head" to the seat or saddle 26 so that steering of the velocipede may be easily effected by simply swinging the yoke to one side or the other.

25 The rear body section 14 is provided with downwardly and rearwardly extending, transversely spaced leg members 34 terminating at their lower ends in rearwardly directed hoofs 36, while a transverse axle 38 is rotatably journaled in suitable anti-friction bearings 40 in the lower end portions of the leg members 34 and has secured thereto a pair of transversely spaced traveling wheels 42, equipped with rubber tires.

30 The lower end portions of the leg members 34 are hollow so as to accommodate the bearings 40 and the wheels 42 and a sprocket 44 is secured to an intermediate portion of the axle 38 and is operatively connected by a chain drive 46 to a further sprocket 48 which, in turn, is secured to 45 a transverse crankshaft 50 rotatably journaled in a bracket 52 which is secured to and extends downwardly from the body section 14.

The lower end portion of the bracket 52 is forked to receive the sprocket 48 between its 50 furcations, and it is to be noted that suitable foot pedals 54 are provided on the "cranks" of the shaft 50, whereby the entire velocipede may be propelled along the ground or floor.

55 The front body section 12 is provided with a pair of downwardly and forwardly extending leg

members 56, the lower end portions of which are relieved as indicated at 58 so as to accommodate suitable casters 60 which permit the entire device to freely travel along the ground and, at the same time, facilitate lateral movement of the front body section 12 relative to the rear body section 14 while steering.

The casters 60 are equipped with rubber tires and antifriction bearings, both on their horizontal axles and vertical fulcrum pins, the latter being indicated at 62 in Figure 1.

It is believed that the advantages and use of the invention will be clearly understood from the foregoing disclosure and, accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

In a velocipede, the combination of an elongated body comprising a front section including a forwardly projecting head and a pair of transversely spaced and forwardly projecting front legs, a rear section including a pair of transversely spaced and rearwardly projecting rear legs, a vertical hinge connecting the front and rear sections together and having its axis disposed substantially midway between the extremi-

ties of the front and rear legs, a transverse axle secured to the rear legs, a pair of transversely spaced wheels mounted on said axle, a pair of casters having vertical pivots in the respective front legs and providing rolling supports for the front body section when it is swung laterally relative to the rear body section about the axis of said vertical hinge, and a substantially U-shaped rigid steering yoke secured at the ends thereof to opposite sides of said head and extending rearwardly therefrom, the bight portion of said yoke being disposed adjacent the vertical axis of said hinge whereby the front body section may be swung about said hinge with minimum of movement of the bight portion of said yoke.

FRANCIS B. LOLMAUGH.
